UNITED STATES PATENT OFFICE

JUSTUS J. ROSS, OF HUNTINGTON, WEST VIRGINIA

METALLIC TIE AND ALIGNMENT LUG THEREFOR

Application filed April 23, 1929. Serial No. 357,491.

This invention relates generally to the improvement of rail ties and has special reference to metallic ties for use in coal mines and the like. Such ties are usually provided with some means for digging into the floor of the mine to prevent lateral shifting of the track, and an object of the present invention resides in provision of a novel type of alignment lugs for this purpose.

10 A further object of the invention resides in combining with the alignment lugs, means for reinforcing the ties at that portion most requiring it, namely, the point where the rail rests on the tie. Obviously, if the tie is not properly reinforced at this point the tie will bend between the alignment lugs, defeating the purpose of these lugs.

20 A further object of the invention consists in providing a structure in which the alignment lug, reinforcing member, and rotatable clip for locking the rail to the tie may all be united by a single securing means, thereby greatly reducing the cost of manufacture.

25 Other objects and advantages of the invention will be apparent from the following description when taken in connection with the accompanying drawings; in which—

30 Figure 1 is a fragmentary longitudinal section through a tie showing one form of the alignment lugs and related parts.

Figure 2 is a section taken on line 2—2 of Figure 4.

Figure 3 is a section on line 3—3 of Figure 4.

35 Figure 4 is a bottom plan view of the construction shown in Figure 1.

Figure 5 is a fragmentary longitudinal section through a tie showing a modified form of reinforcement plate and alignment lug.

40 Figure 6 is a plan view of the structure shown in Figure 5, parts being broken away to more clearly show the construction.

Figure 7 is a transverse section through the tie of Figure 5; and

45 Figure 8 is a detail view of a still further modified form of alignment lug.

Referring to the drawings in greater detail and especially to Figures 1 to 4 inclusive, the numeral 1 indicates a metal cross-tie of a type used in coal mines and the like. The particu-

lar tie shown is provided with longitudinally extending side portions 2 which have formed thereon the horizontally disposed flanges 3 adapted to rest on the floor of the mine. It is to be understood, however, that the present invention is in no way restricted to this particular type of tie but on the contrary is adapted for mine ties of any conventional construction.

55 Mounted on the top of the tie for pivotal movement are clips 4 adapted to cooperate with the base of the rail 5 to secure the same to the tie. These clips are pivoted to the tie by fastening means 6, being indicated in the present disclosure as rivets. Any preferred type of clip may be employed as they form no part of the present invention except in so far as they are combined with the other elements now to be described.

60 Tracks are laid on mine floors without ballast and it therefore becomes necessary to provide some means for cooperation with the floor to prevent lateral movement of the track so as to maintain the track in alignment, i. e., prevent straight track from becoming crooked, and curves from shifting their position. For this purpose I have provided alignment lugs of several different types adapted to be secured to the bottom of the ties so as to be forced into the ground when the track is laid

65 or when the cars traverse the track. One of the novel features of the invention resides in securing the alignment lugs to the tie with the same means by which the clips 4 are attached. To this end the rivets 6 employed are of sufficient length to extend through openings in the body portion of the alignment lugs. In the disclosure of Figures 1 to

70 4 inclusive, a reinforcing plate 7 is placed under each end of the tie at the point where the rail rests and is apertured to receive the rivets 6. Alignment lugs 8 are struck from the plate 7 and, as indicated in Figure 1, are disposed adjacent each side of the base of the rail 5. It will thus be seen that the rivets 6 serve to secure the alignment lugs, reinforcing plate and rail clips to the tie.

75 In view of the considerable strain often placed upon the alignment lugs it is desirable that they be strengthened as much as pos-

55

sible, and for this purpose I deflect a portion of the flanges 9 of the plate 7 inwardly as indicated by numeral 10. These inwardly deflected portions are preferably welded to the sides of the lugs 8 and serve to greatly 5 reinforce them against bending strains caused by traffic on the rails.

In the modified construction shown in Figures 5, 6 and 7 the alignment lugs are formed as a separate element from the reinforcing plate and the latter therefore may be placed 10 on top of the tie where it will be in direct contact with the base of the rail. In this form of the invention the tie is indicated by the 15 numeral 20, and the rail clips 21 and 22 are pivoted thereto by means of the rivets 23; the reinforcing plate 24 being interposed between the clips and the top of the tie thereby not only reinforcing the tie but also serving 20 to prevent wear on the tie by reason of the rotation of the clips 21 and 22. The alignment lugs employed in this form of the invention are angle irons and are provided with the prongs 25 and base portion 26. This base 25 is apertured to receive the lower end of the rivet 23 by which it is secured to the tie, and itself serves as a reinforce for the tie and a washer for the lower end of the rivet. In this form of the invention, as well as in 30 the form previously described, all of the elements, namely, the rail clips, reinforcing plates, and alignment lugs, are secured to the tie by a single rivet, thereby not only providing a compact and rigid structure but also reducing the cost of manufacture. 35

In the modified form of the invention shown in Figure 8, the separate alignment lug is omitted and in lieu thereof I shape the lower head of the attaching rivet 30 into a 40 pointed projection 31 which will penetrate the ground in the same manner as heretofore described in connection with the other forms of the invention, and will hold the track against lateral displacement.

45 From the foregoing description taken in connection with the accompanying drawings it will be observed that I have devised a simple and inexpensive construction of alignment lugs, several examples of which are 50 shown herein, and that I have further devised a novel arrangement of rail clips, tie reinforcing plates and alignment lugs, whereby the same are all united to the tie by a single fastening means thereby not only simplifying 55 and reducing the cost of manufacture of the tie, but also providing a stronger and more durable construction; and that the reinforcing means is so disposed as to prevent bending of the tie with a consequent displacement of 60 the alignment lugs.

In accordance with the patent statutes I have described what I now believe to be the best embodiment of the invention, but I do not wish to be understood thereby as limiting 65 myself or the scope of the invention, as many

changes and modifications may be made without departing from the spirit of the invention; all such I am to include in the scope of the appended claims.

What I claim as new and desire to secure 70 by Letters Patent is:

1. In a metallic cross-tie, a reinforcing plate secured to the under side thereof, and one or more alignment lugs struck from said plate. 75

2. In a metallic cross-tie having downturned, longitudinal flanges, a flanged reinforcing plate secured to the under side of said tie, and downwardly-extending alignment lugs struck from said plate. 80

3. In a metallic cross-tie having downturned, longitudinal flanges, a flanged reinforcing plate secured to the under side of said tie, downwardly-extending alignment lugs struck from said plate, a portion of one of the flanges on said plate being bent inwardly and welded to a side of one of said lugs. 85

4. In a metallic cross-tie having downturned, longitudinal flanges, a reinforcing plate provided with downturned, longitudinal flanges, means for securing said plate to the tie, a plurality of alignment lugs struck from the plate, portions of the flanges on said plate being bent inwardly and welded to the sides of said lugs. 90

5. In a metallic cross-tie having downturned, longitudinal flanges, a reinforcing plate provided with downturned, longitudinal flanges, a plurality of alignment lugs struck from said plate, means for securing 95 said plate to the under side of the tie, and a rail clip pivoted on said plate securing means. 100
